UNITED STATES PATENT OFFICE.

CHARLES M. SNIDER, OF COLUMBUS, OHIO, ASSIGNOR TO THE JEFFREY MANUFACTURING COMPANY, OF COLUMBUS, OHIO, A CORPORATION OF OHIO.

SPROCKET-WHEEL.

1,244,384.

Specification of Letters Patent.

Patented Oct. 23, 1917.

Application filed September 26, 1913. Serial No. 792,003.

To all whom it may concern:

Be it known that I, CHARLES M. SNIDER, a citizen of the United States, residing at Columbus, in the county of Franklin and State of Ohio, have invented certain new and useful Improvements in Sprocket-Wheels, of which the following is a specification, reference being had therein to the accompanying drawing.

10 This invention relates to sprocket wheels of the type disclosed in the patents of William W. Willson, Nos. 649,563, 948,385 and 994,896. The object of the present invention is to provide for sprocket wheels of this general type an improved means for adjusting the tooth-carrying sections outward and inward with respect to the central or hub section.

20 Of the accompanying drawings, which illustrate one embodiment of the invention,

Figure 1 is a side elevation of a sprocket wheel with some of the parts broken away.

25 Fig. 2 is an enlarged fragmentary sectional view taken along the line 2—2 of Fig. 1.

Fig. 3 is a detail fragmentary sectional view showing the means for adjusting one of the tooth-carrying sections. It is taken 30 along the line 3—3 of Fig. 2.

Fig. 4 is an enlarged fragmentary sectional view taken along the line 4—4 of Fig. 1.

Referring to the drawings, 1 represents 35 the main central or hub portion of the wheel which is centrally apertured and adapted to be mounted on a suitable shaft which is not shown. Mounted upon this main central section are several segmental tooth-carrying 40 sections 2, 2, five such sections being shown in the present instance. Each of the sections 2 is made up of two separate parts 2^a, 2^a which are oppositely notched to engage each other and which are connected together 45 by means of a bolt 3 passing through suitable slots. Each of the sections 2 is provided with a peripheral groove adapted for the reception of a rope or cable 4, and with guide teeth 5, 5 adapted to coöperate with 50 the groove to hold the cable in place.

The peripheral curvature of each section 2 is formed with a radius considerably less than the radius of the wheel as a whole. It is necessary to provide short gaps between 55 each section and the next and the cable will

necessarily lie straight across the gaps. If the peripheries of the sections were formed with the center of the wheel as the center of curvature, the cable would necessarily be sharply bent at the end of each section with 60 resulting wear and deterioration. By forming the sections with smaller radii, as shown, each straight section of the cable is tangent to each adjacent curved section, with the result that the cable is not subjected to any 65 sharp bending.

At the end of each of the sections 2 there is provided a pivoted tooth 6 of the sort shown and described in the several patents above referred to. As the construction and 70 operation of the sprocket wheels having teeth of this sort are now well known and understood, it will not be necessary to enter into a detailed description. It is sufficient to point out that the teeth are pivoted in 75 order that they may be enabled at each revolution to travel for a short distance in a straight line under the influence of one of the sprocket blocks 6^a secured to the cable, instead of following its normal curved path. 80 In this way the wear between the teeth and the sprocket blocks is greatly reduced.

Adjacent each part 2^a of the tooth-carrying sections the hub section 1 of the wheel is provided with a pair of oppositely disposed 85 notches 7, 7 which are separated by a centrally disposed rib or web 8. Each part 2^a is provided with two oppositely disposed lugs 9, 9 adapted to enter the notches 7, 7 and to embrace the web 8. The edges of the 90 notches 7, 7 are parallel, as are also the edges of the lugs 9, 9. The edges of the lugs engage the edges of the notches and in this way the parts 2^a are positively guided for movement inward or outward and are firmly 95 held against movement peripherally of the wheel.

Each part 2^a is provided with a hole 10 which is enlarged at its outer end. In register with the hole 10 in the part 2^a is a hole 100 11 in the central hub section. A bolt 12 extends through the holes 10 and 11 and has its head positioned in the enlarged part of the hole 10. The other end of the bolt is threaded and is engaged by a nut 13. It 105 will be seen that by means of this bolt and nut the part 2^a may be drawn inward and may be firmly locked against outward movement. As shown, in Figs. 1 and 3 each of the webs 8 is provided with a transverse 110

slot in which is located a nut 14. Through this slot there extends a hole 15 which is parallel to the holes 10 and 11. A bolt 16 extends through the hole 15 and through the nut 14. It engages at its outer end with the corresponding part 2^a, and it will be seen that by turning the bolt 16 an outward pressure can be exerted on the part 2^a.

It will be clear that by means of the two bolts 12 and 16 each part 2^a can be moved inward or outward as desired and locked in adjusted position. It will be understood that when adjustment is to be made the nuts on the bolts 3 will be loosened. After adjustment has been made these nuts are tightened and assist in holding the parts 2^a, 2^b against relative movement.

The radial adjustment of the tooth-carrying sections is essential in order to make the pitch of the wheel the same as the pitch of the sprocket blocks on the cable. During use the cable will stretch and the pitch of the blocks will be changed. In order for the most efficient operation of the wheel it must be adjusted from time to time to correspond with the change in the rope.

I am aware that in the Willson Patent, No. 994,896, above referred to, it was proposed to provide an adjustment by means of a bolt. In the present construction inclined guideways and similarly inclined tooth-carrying sections secure a number of advantages. The lines upon which each tooth section moves outward are such that its teeth can be carried, not alone outward but, to a marked extent, peripherally, so that the driving teeth can be advanced toward the sprocket gaps a relatively long distance to modify the pitch distance between one driving tooth and the next, the long slot and pin connections at 3 permitting this peripheral movement.

Again, the tangentially inclined shanks of the tooth sections and the tangentially arranged adjusting screws are in such position that the screws are practically relieved of all stress either on their threads or on lines transverse to their axes. The back pressure on a driven tooth section is transmitted to the metal of the rim at the rear edge of its inclined guideway. The inward pressure on the tooth section is taken on the opposite edge of the rim and shank. This, as stated, relieves the bolts of a large part of the strains.

What I claim is:

1. A cable sprocket wheel having a center hub section with a rim having guideways formed on lines tangential to circles around

the hub, tooth carrying elements having shanks fitting in the said guideways and held thereby against circumferential movement, means for adjusting the tooth-carrying elements in said guideways whereby they are moved both peripherally and also outward and inward relatively to the wheel axis, and means for locking the tooth-carrying elements in position after adjustment.

2. A cable sprocket wheel having a hub section formed with guideways in pairs, one guideway of each pair being on lines tangential to circles around the axis and at one side of the axis, and the other guideway of each pair being on lines tangential at the other side of the axis to circles around it, tooth-carrying sections each formed of two adjustably connected companion elements, each element having a guide shank fitted in one of the said guideways and held thereby against circumferential movement, means for adjusting each part of each tooth element outward and inward and also peripherally, and means for locking it in position after adjustment.

3. A cable sprocket wheel having a hub section provided with guideways in pairs and at points remote from the axis, each guideway of each pair being on lines inclined inward and toward the lines of the other guideway and inclined to the radii of both guideways, tooth-carrying sections each formed of two overlapping companion elements adapted to be clamped together and to have the teeth of one move peripherally of the wheel relatively to the teeth of the other and each section having an adjustable guide part fitted in one of said guideways and held thereby against circumferential movement, and means for clamping said sections rigidly in operative position after adjustment.

4. A cable sprocket wheel having a hub section with peripheral guideways formed on right lines, tooth-carrying elements having shanks fitting in the said guideways and held thereby against circumferential movement, and means for adjusting each tooth-carrying element inward and outward and locking it in adjusted position comprising a screw bolt for positively moving said element outward and a second screw bolt for positively moving said element inward.

In testimony whereof, I affix my signature, in presence of two witnesses.

CHARLES M. SNIDER.
